APPARATUS FOR SOLIDIFYING AND PRESSING CARBON DIOXIDE AND THE LIKE

Adolph Schutz, Wurzen, Germany, assignor, by
mesne assignments, to International Carbonic
Engineering Company, Wilmington, Del.

Application February 3, 1936, Serial No. 62,209
In Germany February 12, 1935

26 Claims. (Cl. 62—121)

This invention relates to certain improvements in apparatus for solidifying and pressing carbon dioxide and the like, and the nature and objects of the invention will be readily recognized and understood by those skilled in the art in the light of the following explanation and description of the accompanying drawings illustrating what I now believe to be the preferred embodiments or mechanical expressions of my invention from among various other embodiments, arrangements, designs, constructions and combinations of which the invention is capable within the spirit and scope thereof.

5

Solidified carbon dioxide is now in wide commercial use as a refrigerant and for various other purposes. In accordance with generally prevailing practices and methods for the production commercially of solidified carbon dioxide, the carbon dioxide is first produced as a solid in crystallized form as more or less loose solid particles or so-called carbon dioxide "snow". A desired quantity or mass of such "snow" is then compressed or compacted, usually by mechanical pressing apparatus, into dense, coherent form as a block or cake capable of structurally withstanding handling and transportation in use.

Attention is here directed to the fact that the term "snow" as used herein is to be interpreted in a broad, generic sense to include the carbon dioxide in its solidified form prior to any pressing or compacting of a mass thereof into a more dense and coherent block or cake form; and is not used in the more limited or strict sense of the small crystal or snow-flake forms resulting from certain methods of carbon dioxide solidification.

The solidification of the carbon dioxide is mainly carried out commercially in two general types of apparatus, in one of which the solidification takes place in the actual pressing chamber of the press apparatus, while in the other type solidification is carried out in a separate chamber in gas-tight communication with the pressing chamber so that the solidified carbon dioxide may pass from the solidification chamber to the pressing chamber. My present invention relates to the latter type of apparatus and is directed toward increasing the efficiency of the type and providing a design and arrangement of apparatus for continuous operation with simultaneous solidification and pressing.

As a factor in the problem of simultaneous solidification and pressing to attain continuous operation of such apparatus, experience has demonstrated the necessity for carrying out the pressing of a mass of solidified carbon dioxide in

a pressing chamber with the chamber at substantially atmospheric pressures and with practically all carbon dioxide gas removed from the chamber before pressing, in order to avoid occluding gas in the block of carbon dioxide produced. If gas is compressed or occluded in the completed block, then when the block is removed from the apparatus at atmospheric pressure, such gas tends to expand and escape from the block with such force as to disrupt the block or impair its coherency and structural strength.

The solidification of the carbon dioxide in the solidification chamber of such types of apparatus is generally carried out by expanding liquid carbon dioxide in the chamber to a pressure below the triple point while withdrawing the resulting expansion gas from the chamber, so that a portion of the liquid is frozen out into solidified form and collects in the chamber. As a result of the liquid expansion in the chamber and gas withdrawal there is established a certain gas velocity in the chamber and a certain part of the solidified particles may become entrained in the gas and be withdrawn with the gas from the chamber. The extent of such entrainment and the resulting amount of solid withdrawn would appear to be dependent upon the gas velocity established in the chamber and the higher the velocity the greater the entrainment and consequently the larger the quantity of solid that may be withdrawn from the chamber.

The gas velocity in a given solidification chamber is mainly determined by the cross sectional area of the solidification chamber, the rate at which the liquid is being expanded in the chamber, the pressure of the liquid before its expansion into the chamber, and the pressure in the chamber down to which the liquid is expanded. Thus, by increasing the cross sectional area of the chamber, or by decreasing the rate of expansion of the liquid into the chamber, or by both these changes, the velocity of the gas in the chamber can be lowered and the possibility of solid entrainment reduced. However, in commercial operation it is desirable from the economy and efficiency standpoint, to produce in a given time as much solid as possible by expanding the liquid carbon dioxide at as high a rate as possible, so that the lowering of gas velocity in the solidification chamber by reducing the rate of liquid expansion is not generally practically feasible or desirable.

With the type of apparatus having the separate solidification chamber, in order to obtain the desired free passage or transfer of the solidified

carbon dioxide from the solidification chamber to the pressing chamber for practical and efficient operation, the cross sectional area at any part of the solidification chamber, or of any passage between such chamber and the pressing chamber, should not be less than or greater than the cross sectional area of the pressing chamber. In other words the cross sectional area of the solidification chamber and any communicating passage, is limited and determined by the cross sectional area of the pressing chamber, and in a practical apparatus may not be increased in order to lower chamber gas velocity but should be the same as the pressing chamber. As low gas velocity is desired, then the cross sectional area of the solidification chamber is made as large as possible within the stated limits, that is, a cross section the same as that of the pressing chamber.

It has been established that the gas velocity in a given solidification chamber decreases with a decrease in the pressure differential between the initial pressure (which must be above the triple point) at which the liquid or fluid carbon dioxide is admitted to the solidification chamber, and the pressure maintained in the chamber during admission (which pressure must be below the triple point) and down to which the carbon dioxide is expanded to produce a portion thereof in the solidified form. Thus, with a solidification chamber of given cross sectional area with a given rate of liquid expansion, by lowering the pressure of the liquid carbon dioxide toward the triple point prior to admission to the chamber and by raising the chamber pressure toward the triple point, thereby reducing the pressure differential, the gas velocity in the chamber may be reduced during solidification without either increasing the cross sectional area of the chamber or reducing the rate of liquid expansion and production of solid.

In solidifying and pressing apparatus of the general types under discussion, experience has shown that when all of the foregoing factors are set for the most efficient practical operation, the rate at which the solidified gas can be pressed in the pressing chamber is much higher than the rate at which the solidified gas can be generated or produced in the solidification chamber, so that, in practice it is found that with the solidification chamber operated at its maximum rate of production, the pressing chamber can only be operated to press the solid at about one-half, or even less, the rate of which it is capable.

My present invention is primarily directed to the provision of carbon dioxide and the like solidification and pressing apparatus of the types having a solidification chamber separate from a pressing chamber, with which apparatus continuous production of blocks of solidified carbon dioxide can be carried out with simultaneous solidification and pressing, and by which the pressing as well as the solidification can be performed at the maximum rates of production of which the solidification chamber and pressing chamber or unit of a given apparatus are capable.

A further aim and feature of the invention is to provide such an apparatus for continuous and simultaneous solidification and pressing at maximum production rates, with which solidification methods may be carried out which require the maintenance of above atmospheric pressures in the solidification chamber during solidification, yet which apparatus can be operated for

simultaneous solidification and pressing while eliminating above atmospheric pressures in the pressing chamber and the resulting occluded gas in the completed blocks, without interference with the maintenance of the desired above atmospheric pressures in the solidification chamber during solidification, so that the advantages of the hereinbefore referred to methods of solidification which utilize such pressures may be obtained for the apparatus.

A feature of the invention in carrying out the foregoing general object of simultaneous solidification and pressing with continuous solid carbon dioxide block production, resides in the provision of a design and construction of apparatus in which a single press unit is supplied with solidified carbon dioxide from a plurality of solidification chambers in such a manner that the pressing chamber can be maintained substantially free of gas and at atmospheric pressures without interrupting the production of solid carbon dioxide in the solidification chambers, and the press unit can be continuously operated to press the solidified carbon dioxide into blocks without interruption due to the solidification of the carbon dioxide in the solidification chambers or transfer of such solid to the pressing chamber.

A further feature of apparatus of the invention is embodied in the arrangement of the solidification chambers and the pressing chamber of the press unit, by which the solidification chambers are maintained closed to the atmosphere at all times during solidification therein and transfer of solid therefrom to the pressing chamber of the press unit; and by which the pressing chamber is maintained closed to atmosphere during charging with solid and pressing of such solid therein.

A further feature of the invention is found in the arrangement for transferring measured charges of solidified carbon dioxide from a plurality of solidification chambers to the pressing chamber of a single press unit associated with such solidification chambers to form a solidification and pressing apparatus in accordance with my invention.

An object of the invention is also to provide a practical and efficient design and construction of apparatus embodying the foregoing general features and for attaining the results generally referred to, which design and construction is mechanically simple and of relatively low cost to build yet will be capable of efficient operation under actual production conditions.

With the foregoing general features, objects and results in view, as well as certain others which will be readily apparent from the following detailed description my invention consists in certain novel features in design and construction and in combination of elements, as well as in methods of operation, all as will be more fully and particularly referred to and specified hereinafter.

Referring to the accompanying drawings:

Fig. 1 is a view in vertical cross section, more or less diagrammatic, through a solidifying and pressing apparatus of the invention, and showing solidification taking place in one of the solidification chambers, while the other chamber is filled with solid, and also showing the press unit in position for receiving a measured charge of solid from the filled solidification chamber.

Fig. 2 is a view similar to Fig. 1, but with the movable transfer chamber unit in position discharging a charge of solid from the inactive solidi-

ification chamber to the press chamber of the press unit.

Fig. 3 is a view similar to Fig. 1 but with the transfer chamber unit moved to receive a charge 5 from its solidification chamber, and with the press chamber closed and the press unit in position with the charge of solid therein compacted into a block.

Fig. 4 is a view of the apparatus similar to the 10 preceding views but showing the next charge of solid discharged from the transfer chamber into the intermediate chamber and held therein by the press chamber closing head, while the press unit is in completed block ejecting position.

15 One possible form of apparatus for carrying out and practically embodying the principles and features of the invention is disclosed in the accompanying drawings, and includes in accordance with the fundamentals of the invention, a plurality of separate carbon dioxide or other gas solidification chambers, in this instance consisting of the two chambers SL and SR, associated with a single press unit P through the medium of an intermediate solidified gas measuring and charge 20 receiving chamber M, and the charge transfer-chamber units TL and TR. Such major elements are combined into the apparatus by which the gas is solidified and charges thereof are transferred from the solidification chambers to the 25 press unit in such a manner that solidification can be continuously carried out and the press unit supplied with solidified gas during uninterrupted operation of the press unit.

In the particular design and arrangement of 30 the present example of apparatus, the press unit P includes a base 10 having the vertically disposed, upwardly extending concentric inner and outer fluid pressure cylinders 11 and 12 mounted thereon, with the pressure actuated pistons 14 and 15 respectively, slidably mounted for reciprocation therein. The inner fluid pressure cylinder 11 is provided with the pressure fluid passages 11a and 11b in communication therewith at opposite sides of the piston 14, while the outer cylinder 12 is provided with the fluid pressure 35 passages 12a and 12b opening therewith at opposite sides of its piston 15, referring particularly to Fig. 1 of the drawings.

The cylinders 11 and 12 are connected through 40 their respective passages 11a and 11b and 12a and 12b, with any suitable source of fluid pressure (not shown) for control of such pressure to the cylinders in the usual or any desired manner to raise and lower the pistons 14 and 15 under 45 the required pressures. It is not deemed necessary to here disclose such a source of fluid pressure or any control means for actuating the pistons 14 and 15, in view of the fact that any of a variety of known arrangements may be employed, and the means for operating and controlling the 50 pistons 14 and 15 forms no part of the invention hereof.

The piston 15 of the outer cylinder 12 is of an 55 annular or ring form concentric with and slidably engaging the outer wall surface of the inner cylinder 11, and is provided with an upwardly extending sleeve 16. The press cylinder 17, which provides the solidified gas pressing chamber, is in this instance directly carried on and as an upward continuation of the upwardly extending sleeve 16 of piston 15. The piston 14 in the inner cylinder 11 is provided with a piston rod 18 that extends upwardly therefrom and outwardly through the closed upper end or head of

cylinder 11 in which it has a sliding and sealing fit, and this piston rod is in axial alignment with the press cylinder 17. A pressing head or plunger 19 is mounted on the upper end of piston rod 18 and is slidably received in and forms the lower end closure for the press cylinder 17, so that the plunger 19 is reciprocal in cylinder 17 by the fluid pressure actuation of piston 14, and/or by relative movement between press cylinder 17 and its pressing plunger 19.

The press cylinder 17 is raised and lowered by the fluid pressure actuated piston 15 in cylinder 12, independently of the actuation of plunger 19 by piston 14, and it is to be noted, by reference to Fig. 4 of the drawings, that with the press cylinder 17 and its pressing plunger 19 both in their lower-most positions, the plunger 19 is positioned at the upper end of the press cylinder with its upper surface at least flush with the upper edge of the cylinder or even above the press cylinder 20 upper edge. In raised position of the press cylinder 17 and lowered position of plunger 19, the latter is positioned in the lower end of the press cylinder for upward movement by piston 14, in the press cylinder to press a mass or charge of 25 solidified gas in the cylinder against a suitable abutment element or head closing the upper end of the press cylinder.

A housing or platform structure 20 is supported in horizontally disposed position above 30 the press cylinder 17, by the spaced, vertical columns 10' carried by base 10 at opposite sides of the fluid pressure cylinder 12. The structure 20 provides and includes the vertical passageway or chamber M there-through which is open at its 35 upper end and at its lower end opens into a transverse, horizontal slideway 21 formed in the housing structure 20. The chamber M is vertically axially aligned with the press cylinder 17 and has the same internal diameter as that of the press- 40 ing chamber formed by the press cylinder. At the lower or under side of slideway 21, the housing structure is provided with a vertical opening or passage 22 there-through axially aligned with chamber M and of a diameter to receive and seat the upper end of press cylinder 17 when the latter is in the raised charge receiving and pressing positions of Figs. 1 to 3. The upper end of press cylinder 17 has a reduced diameter in the example hereof to form a shoulder 17a (see Fig. 4) 45 which may if desired engage the under side of structure 20.

A slide or gate valve 23 is slidably mounted and confined in slideway 21 of structure 20, and includes a vertical port or opening 24 there-through having a diameter equal to the internal diameter of press cylinder 17 and charge receiving and measuring chamber M. This slide 23 is movable in slideway 21 to the position shown in Figs. 1 and 2, in which its port 24 is aligned 55 with chamber M and the open end of press cylinder 17, so that there is formed a continuous, unbroken passage through chamber M and port 24 into the press cylinder. Preferably, the slide 23 forms a substantially sealing fit in its slideway, and the upper end of press cylinder 17 in raised position forms a substantially sealed fit in opening 22, so that the chamber M, port 24 and press cylinder chamber when together as shown in Figs. 1 and 2, form a chamber or space 60 substantially closed to atmosphere. From position placing chamber M and the pressing chamber of cylinder 17 in communication, the slide 23 is movable, to the left in Figs. 1 and 2, to remove port 24 from connecting alignment between 65 70 75

chamber M and press cylinder 17, and to place the slide in position closing and shutting off the chamber M and press cylinder from each other, while forming a closure head for the upper end 5 of the press cylinder when in raised position, as shown in Fig. 3 of the drawings.

Suitable means is provided for actuating the slide 23 and in the example hereof takes the form of a pressure fluid cylinder 25 mounted at one 10 end of slideway 21 and having a piston 26 therein with a piston rod 27 extending therefrom to and operatively connected with the slide. The cylinder 25 is formed with the pressure fluid passages 25a and 25b (see Fig. 1) thereto at opposite 15 sides of piston 26, which passes are connected with a source of fluid pressure and are opened and closed in the usual manner, to cause piston 26 to move slide 23 to the desired positions.

The gas solidification chambers SL and SR are 20 supported in vertical position spaced above structure 20 on a base 30 which is fixed in position spaced above and parallel with the upper side wall 20' of the lower housing structure 20 by suitable end walls 31, and if desired spaced side 25 walls (not shown), to form a slideway therebetween for the movable transfer chamber units TL and TR. The solidification chambers SL and SR are in the example hereof, of elongated tubular form and are mounted spaced apart on base 30 at diametrically opposite sides of and spaced 30 equal distances from the measuring or charge receiving chamber M in the housing structure 20. The solidification chambers are mounted and secured in suitable openings in the base 30 and 35 are open at their lower ends into the slideway formed by and between wall 20' and the base 30.

The transfer chamber units TL and TR are 40 each formed by a cylinder or tubular structure that provides a vertical open ended chamber therethrough and are of a height or depth equal to the space between the wall 20' and solidification chamber supporting base 30. The units TL and TR are mounted in the space between wall 20 and base 30 to form a freely sliding but preferably sealing engagement at their upper and 45 lower sides or ends with the inner surfaces of the base 30 and wall 20', respectively, so that the units may be slid or moved between the solidification chambers and the charge receiving chamber M. In normal inactive position the transfer 50 chamber units TL and TR, which have internal diameters equal to the internal diameters of the solidification chambers, are in positions beneath and vertically alined with the chambers SL and TR, respectively, so that the open upper ends of 55 the transfer chambers register and join with the open lower ends of the solidification chambers and the transfer chambers form continuations of and receive material from the solidification chambers, as shown in Figs. 1 and 3 of the drawings. The lower open ends of the transfer chamber units TL and TR when in the foregoing 60 positions are closed by the wall 20' forming the lower track of the slideway for the units

65 Each transfer chamber unit TL and TR is formed with a horizontally disposed closure plate 32 extending from the upper side thereof outwardly toward the adjacent outer end of the slideway, and these closure plates form a sliding and preferably sealing engagement with the under 70 surface of the base 30 which forms the upper track of the slideway.

Each of the sliding transfer units TL and TR is 75 operatively coupled with a means for moving the unit between position alined with a solidifica-

tion chamber and position alined with the charge receiving chamber M. In the present example such actuating means are of the fluid pressure operated type and for each unit comprise a fluid pressure cylinder 33 mounted in the end wall 31 5 of the slideway adjacent the respective transfer chamber unit, and extended a distance into the slideway. Each cylinder has a piston rod 35 extended to and connected with the piston so that by reciprocating the piston the transfer unit with 10 which it is coupled is moved between a solidification chamber and the chamber M. The transfer chamber units are connected with a source of fluid pressure and means (not shown) are provided for controlling the pressure fluid and admitting it to the cylinders to reciprocate pistons 15 34 to obtain the desired movement and position for the transfer units, as will be readily understood by those skilled in the art.

The gas solidification chambers SL and SR are 20 connected with a source of liquefied gas, which for the purposes of the present example is a source of liquefied carbon dioxide, and each is provided with a suitable pipe or nozzle 40 for discharging the liquefied carbon dioxide into the chamber for 25 expansion and conversion of a portion of the liquid to solid carbon dioxide or "snow", and the remainder to gaseous carbon dioxide. The upper end of each chamber is also provided with a gas withdrawal or offtake conduit 41 through which 30 the expansion gases are withdrawn from the chamber. The liquid carbon dioxide is supplied to the discharge or nozzle 40 of a solidification chamber from a suitable source by the pipe 42 having the liquid carbon dioxide supply controlling and shut-off valve 43 therein.

In accordance with one possible method of solidification, the liquid carbon dioxide is brought to the solidification chamber (the pressures given are gauge pressures) with its pressure reduced to 40 near the triple point of carbon dioxide, say, with the pressure on the liquid reduced to a pressure of the order of approximately 8 atmospheres. The liquid at this reduced pressure is then discharged into the solidification chamber in which a pressure is maintained above atmospheric, say, of the order of approximately 3 atmospheres, so that the liquid is expanded to a pressure below its triple point of 4.28 atmospheres (5.28 ats. absolute) 45 with the resulting freezing out of a portion of the liquid as solid while the remainder gasifies. The solid is collected in the chamber and the expansion gases are withdrawn from the chamber at a rate in relation to the liquid discharge rate, and other controlling factors, to maintain the required pressure of the order of 3 atmospheres in the solidification chamber. By such method not only is there a greater percentage of solid obtained from the liquid due to the lowered temperature from the pressure reduction of the liquid, but also by reducing the pressure differential 50 between the chamber or solidification pressure and the liquid pressure, the gas velocity in the chamber is lowered and the tendency of the withdrawn gas to carry off particles of the solid or 55 "snow" by entrainment is thereby reduced.

With such methods of solidification it has been found in practice that the liquid carbon dioxide cannot be safely reduced in pressure below a gauge pressure of the order of about 7 atmospheres, and in fact a minimum pressure of the order of 8 to 8½ atmospheres with a normal working pressure of about 9½ to 10 atmospheres may be said to be preferable. The lower pressures stated above may be successfully used with a 60 70 75

plant in continuous operation, but the higher pressures should be employed when the plant is working intermittently. Obviously, a minimum pressure must be employed for the liquid that is sufficiently above the triple point to provide a margin of safety for a fall or drop in pressure in the liquid line, such as might be caused by a leak or resistance to liquid flow. Upon such a fall in pressure a part of the liquid will expand and if the triple point is reached solidification of a part will result tending to cause the liquid line to freeze up.

With respect to the above atmospheric pressure in the solidification chamber, such pressure must of course be maintained below the triple point pressure of 4.28 atmospheres, gauge, and experience has shown that such pressure may not practically approach too close to the triple point. If the pressure is too close to the triple point in a process operating at high speed there is the possibility of carrying some unexpanded liquid into the solid and if the solid be immediately pressed with such liquid present, there would be occluded gas in the pressed block. For such reason, the maximum solidification chamber pressure in practice should preferably not exceed a gauge pressure of the order of 3 atmospheres, and may even be of the order of 2 atmospheres.

The expansion gas withdrawal conduits or gas offtake lines 41 from the solidification chambers SL and SR are connected with the intake of a gas compressor (not shown) or other source to which the gaseous carbon dioxide from the solidification chambers is withdrawn, and may be then recompressed and reliquefied for return to the solidification chambers as liquid for further expansion and solidification.

With the solidification and pressing apparatus of the embodiment hereof in operation and carrying out the carbon dioxide solidification method as described, referring now to Fig. 1 of the drawings, the transfer chamber units TL and TR are moved to and held in the positions alined with and forming the lower end portions of chambers SL and SR, respectively, with the lower ends of the transfer units, that is to say, the solidification chambers, substantially sealed and closed to atmosphere by the upper wall 20' of the housing structure 20. Liquid carbon dioxide at the reduced pressure of approximately 8 atmospheres has been expanded into solidification chamber SR in which the pressure has been maintained at approximately 3 atmospheres, and the resulting solidified carbon dioxide has been collected in the chamber formed by the transfer chamber TR and solidification chamber SR, while the expansion gas has been withdrawn through conduit 41, until the chamber is substantially filled with solid or "snow" as indicated. When filled the liquid supply line is shut off by valve 43, and the pressure in the chamber is allowed to fall to atmospheric and the mass of more or less loose crystals of the solidified carbon dioxide is ready for transfer to the press unit P.

The solidification chamber SL, which may have been emptied of its solid, is again being charged with solid by maintaining the above atmospheric pressure therein of approximately 3 atmospheres and discharging the liquid carbon dioxide at a reduced pressure of approximately 8 atmospheres through discharge pipe 40 into the chamber while withdrawing the expansion gas through conduit 41. At this point attention is called to the fact that while the particular method of solidifying the carbon dioxide of the invention is described

as employed in filling the solidification chambers of the apparatus, and while such method may be preferred, yet the apparatus of the invention is not limited to use with such method, and any other desired or suitable solidification method for carbon dioxide or any other gas may be utilized in the apparatus if so desired.

While the chamber SL is being filled, the filled chamber SR in which atmospheric pressure preferably prevails, is to have its solidified carbon dioxide transferred to the press unit P. The press cylinder 17 is raised to position of Fig. 1 by the fluid pressure piston 15, with its open upper end received in passage 22 and thus placed in direct unobstructed communication with chamber M through port 24 of slide valve 23, which latter is moved to position registering port 24 with chamber M and the raised press cylinder by fluid pressure cylinder 25. The pressing plunger 19 is maintained in its lowered position at the lower end of and closing the press cylinder chamber preparatory to receiving a charge of solidified carbon dioxide in the press cylinder.

With the elements of the press unit so positioned, the transfer chamber unit TR, which is filled with a charge of solidified carbon dioxide, is moved by its actuating piston 33 in the slide-way into registration with the intermediate or measuring chamber M and the charge of solid in the transfer unit falls by gravity through chamber M and port 24 into the pressing cylinder 17, as clearly shown by Fig. 2 of the drawings. As the transfer unit TR is moved from alignment with the lower end of chamber SR, the closure plate 32 carried by the unit, slides across and closes the lower open end of the solidification chamber, as shown by Fig. 2.

After the charge in the transfer unit TR is transferred into the press cylinder 17, referring now to Fig. 3 of the drawings, the slide valve 23 is moved by its actuating cylinder 25 to close the upper end of the charged pressing cylinder and to form the bottom closure for the chamber M. The transfer unit TR is then moved back to position alined with solidification chamber SR and the column of solidified carbon dioxide therein drops downwardly to again fill the transfer chamber unit preparatory to transferring such charge to chamber M. While the transfer unit TR is being returned to and filled from chamber SR, the pressing plunger 19 is forced upwardly by the fluid pressure piston 14 in cylinder 11 under sufficient pressure to press the charge of solidified carbon dioxide in the pressing cylinder against slide 23 which forms the closure head for the press cylinder, into a dense block B of solid carbon dioxide as shown in Fig. 3 of the drawings.

Meanwhile, the charged transfer unit TR is again moved into alinement with chamber M, the lower end of solidification chamber SR being closed by plate 32, and its charge is dropped into the chamber M and is held therein on slide M which closes the lower end of this chamber, preparatory to movement into the pressing chamber of pressing cylinder 17, as will be clear by reference to Fig. 4.

Upon completion of the block B in the upper end of press cylinder 17, as shown in Fig. 3, the press cylinder is lowered with the pressing plunger 19, by operation of fluid pressure cylinders 12 and 11, but as the downward movement of the press cylinder is greater than the downward movement of the pressing plunger, such cylinder moves downwardly past and relatively to the plunger after the latter has reached its down- 75

ward limit of movement, so that the block of solidified carbon dioxide B is in effect ejected from the pressing cylinder and exposed supported on the upper end of the plunger 19 for ready unobstructed removal from the apparatus. The foregoing block ejecting position of the press cylinder and plunger of the press unit P is clearly shown in Fig. 4 of the drawings.

Upon removal of the completed block B from the apparatus, the pressing cylinder 17 is again raised to charge receiving position of Fig. 1, and the slide 23 is moved to register its port 24 with pressing cylinder 17 and intermediate chamber M, so that, the charge of solidified carbon dioxide previously transferred to and held in chamber M, is released and falls into the charges the pressing cylinder to be pressed therein into a block by the pressing plunger, in the manner above explained. The sequence of operations of transferring charges from solidification chamber SR to chamber M and the pressing cylinder, by transfer unit TR, and the pressing of such charges into blocks is continued until the mass of solid in chamber SR has been transferred charge by charge to the press unit P and converted into blocks. The transfer of the solid from the solidification chamber SR and the pressing of the solid into blocks is carried out with the solidification chamber and the pressing chamber at substantially atmospheric pressure, and with substantially all of the carbon dioxide gases removed from the solidification chamber, so that, the occluding of such gas into the blocks is practically eliminated.

The solidification of the carbon dioxide in the chamber SL is carried on during the transfer of the mass of solid from the inactive chamber SR to the press unit P, and the chamber SL will be filled and prepared to supply solid to the press unit as soon as chamber SR has been emptied. When chamber SR is emptied, its transfer unit TR is moved back to the position of Fig. 1 and solidification of liquid carbon dioxide is started in accordance with the particular method hereof, or any other method, to again fill chamber SR. Filled chamber SL has its pressure brought to atmospheric and solidification stopped, and its mass of solidified gas is then transferred charge by charge to the press unit P, by its transfer unit TL, and converted into blocks in the same manner and by the same series of operations as described in connection with solidification chamber SR and its transfer unit TR.

Thus, with the apparatus of the invention solidification is continuous and block pressing is continuously carried out by a single pressing unit during solidification and without interrupting the pressing operations because of solidification and the conditions established thereby. The use of alternate solidification chambers for solidification and for transfer of solid to the press unit enables the use of any desired and advantageous solidification methods, irrespective of pressures used, and also permits of the transfer of the solid from a solidification chamber to the pressing chamber at atmospheric pressures and with substantially all expansion gas removed so as to reduce and practically eliminate the difficulties of occluded gas in the completed blocks. The transfer of measured quantities of the solidified gas to the press unit, under the above conditions, also materially contributes to the uniform character of the blocks produced by the apparatus.

The example of apparatus of the invention illustrated and described herein, included but

two solidification chambers, but the invention contemplates and includes any desirable number, with a transfer unit for each chamber, or with one or more transfer units serving a greater number of chambers.

It is also evident that various other changes, modifications, variations, additions, eliminations and substitutions might be resorted to without departing from the spirit and broad scope of the invention, and hence I do not wish to limit the invention in all respects to the exact and specific disclosures hereof.

What I claim is:

1. An apparatus for gas solidification and pressing, including in operative combination 15 separate sources of solidified gas, a press unit in normal fixed position relative to said sources, said unit including a pressing chamber for receiving a charge of solidified gas and pressing the same therein into a block, and a charge transfer unit 20 for each of said sources movable between the source and the press unit for transferring a solidified gas charge from the source to the press chamber of the unit.

2. In apparatus for gas solidification and 25 pressing, the combination in operative assembly of a plurality of separate gas solidification chambers, a solidified gas charge receiving chamber spaced from said solidification chambers, and transfer units movable between said solidification 30 chambers and said receiving chamber for transferring a charge of solidified gas from any one of said solidification chambers to said receiving chamber, in combination with a press unit for receiving a charge of solidified gas from 35 the receiving chamber to press such charge into a block.

3. Apparatus for gas solidification and pressing including in combination and operative assembly, separate gas solidification chambers, a 40 press unit including a solidified gas charge receiving and pressing chamber spaced from said solidification chambers, a charge transfer unit for each solidification chamber movable between 45 position receiving a charge from its solidification chamber to position for discharging such charge into the pressing chamber of said pressing unit, and means for actuating said transfer units.

4. Apparatus for gas solidification and pressing, including in combination and operative assembly, separate gas solidification chambers, a solidified gas charge holding chamber spaced from said solidification chambers, a press unit including a solidified gas charge pressing chamber for charge receiving association with said holding chamber, a charge transfer unit for each solidification chamber movable between a position receiving a charge from a solidification chamber and a position discharging such charge into the pressing chamber of the press unit, and means for selectively actuating said transfer units.

5. In gas solidification and pressing apparatus, a solidification chamber, a solidified gas charge receiving and holding chamber remote from the 65 solidification chamber, a pressing chamber having a pressing plunger therein for pressing a charge of solidified gas into a block, said pressing chamber associated with said holding chamber for receiving a charge of solidified gas therefrom, means for opening and closing communication between the holding chamber and the pressing chamber, said means in closing position forming a head against which the charge in the pressing chamber is pressed by said plunger, and a 70 75

charge transfer unit movable between a position receiving a charge from the solidification chamber and a position discharging such charge into the charge receiving and holding chamber.

5 6. In gas solidification and pressing apparatus, the combination and operative assembly of a gas solidification chamber, a press unit having a pressing chamber spaced from said solidification chamber, a transfer unit for receiving a charge 10 of solidified gas from the solidification chamber, said transfer unit in charge receiving position forming a portion of the solidification chamber and movable from the chamber to a position for discharging the charge to the pressing chamber 15 of the press unit, and means for closing the solidification chamber when said transfer unit is moved from charge receiving position.

7. In gas solidification and pressing apparatus, a gas solidification chamber, a solidified gas 20 pressing chamber spaced from the solidification chamber, one end portion of the solidification chamber formed by a movable charge transfer unit, a slideway in which said unit is mounted, said transfer unit movable in said slideway from 25 the solidification chamber to a position for discharging a charge of solidified gas to the pressing chamber, said transfer unit closed by said slideway during movements between charge receiving and charge discharging positions, and a 30 closure member carried by said unit for closing the solidification chamber when the transfer unit is moved from charge receiving position forming an end portion of the solidification chamber.

8. Gas solidification and pressing apparatus 35 including, spaced vertically disposed gas solidification and collecting chambers, a supporting structure for said chambers providing a vertically disposed solidified gas charge receiving chamber positioned intermediate and spaced from said solidification chambers, said supporting structure forming a guideway between said solidification chambers across said receiving chamber, a movable transfer unit for each solidification chamber mounted in said guideway and providing a vertical charge transfer chamber therethrough, and each of said units movable in the guideway between charge receiving position below and in vertical prolongation of a solidification chamber and position above and vertically aligned with said charge receiving chamber for discharge thereto.

9. Gas solidification and pressing apparatus 45 including, spaced vertically disposed gas solidification and collecting chambers, a supporting structure for said chambers providing a guideway across and between the lower ends thereof and having spaced upper and lower walls, a vertically disposed solidified gas charge receiving and holding chamber formed with its upper end 50 opening through the lower wall of said guideway and spaced below and intermediate the lower ends of the solidification chambers, a transfer unit for each solidification chamber providing an open ended vertical chamber therethrough mounted in said guideway and normally positioned in alignment with and forming the lower end portion of a solidification chamber for receiving a charge therefrom, each of said units movable in the guideway between such normal 55 position at its solidification chamber to a position at and aligned with said charge holding chamber for discharging a charge into the latter chamber, said transfer units closed by the walls of the guideway during movements between 60 charge receiving and charge discharging posi-

tions, means for closing the lower end of each solidification chamber when its transfer unit is moved therefrom, and means for selectively actuating said transfer units.

10. A method of producing solid carbon dioxide in the form of snow which includes the steps of; reducing the pressure of liquid carbon dioxide to a pressure close to but definitely above its triple point pressure prior to further expansion of the liquid for solidification; expanding such reduced 10 pressure liquid down to a pressure near to but definitely below the triple point pressure of carbon dioxide in a chamber closed to atmosphere; and maintaining such below triple point pressure in the chamber by withdrawing the gaseous carbon dioxide from the chamber during expansion 15 of the liquid carbon dioxide in the chamber.

11. A method of solidifying carbon dioxide in the form of snow, which includes the steps of; supplying liquid carbon dioxide at a gauge pressure of the order of approximately 8 atmospheres to a chamber closed to atmosphere; expanding the liquid carbon dioxide in the chamber to a pressure close to but below the triple point pressure of carbon dioxide to solidify out a portion of 20 the liquid carbon dioxide as snow; and during expansion of the liquid carbon dioxide in the chamber withdrawing the resulting gaseous carbon dioxide at a rate to maintain the chamber pressure at a below triple point pressure of approximately a gauge pressure of the order of 3 atmospheres. 25

12. A method of producing solid carbon dioxide in the form of relatively loose crystals or snow, which method includes the steps of; supplying liquid carbon dioxide at a pressure near to but definitely above the triple point pressure of carbon dioxide to a chamber closed to atmosphere; expanding such liquid carbon dioxide in the chamber to a pressure below but definitely near to 30 the triple point to convert a portion of the liquid to relatively loose and light crystal or snow form and a portion of the liquid to gaseous form; and during expansion of the liquid in the chamber and production of the snow crystals therein, 35 withdrawing the gaseous carbon dioxide from the chamber at a rate to maintain the pressure in the chamber to which the liquid is expanded near to but definitely below the triple point, whereby to 40 lower gas velocity and reduce entrainment of the snow crystals with the withdrawn gases. 45

13. In apparatus for pressing a solidified gas, including in combination and operative assembly separate sources of solidified gas, a pressing unit for receiving and pressing charges of solidified gas 55 from said sources into blocks, and a separate means for each solidified gas source for transferring charges of solidified gas therefrom to said pressing unit.

14. An apparatus for pressing a solidified gas, the combination and operative association of separate sources of solidified gas, a pressing unit including a pressing chamber for receiving charges of solidified gas from said sources, a separate means for transferring charges of solidified gas from each source to the pressing chamber of 60 said pressing unit, and means for selectively causing said charge transferring means to transfer charges from the respective sources to the pressing unit. 65

15. An apparatus for pressing a solidified gas into blocks, including in combination and operative assembly separate sources of solidified gas, a pressing unit including a pressing chamber for receiving and in which a charge is pressed into a 70 75

block, said pressing unit including means for ejecting a completed block therefrom, and means for transferring charges of solidified gas from any one of said sources to the pressing chamber of said unit.

- 5 16. In gas solidification and pressing apparatus, a gas solidification chamber, a press unit having a solidified gas receiving and pressing chamber spaced from said solidification chamber, a transfer unit for receiving a charge of solidified gas from the solidification chamber, said transfer unit in charge receiving position forming a portion of the solidification chamber and movable from the chamber to a position for discharging 10 the charge to the pressing chamber of the press unit, and means controlled by the transfer unit for closing the solidification chamber when said transfer unit is moved from charge-receiving position.
- 15 17. Gas solidification and pressing apparatus including, a vertically disposed gas solidification and collecting chamber, a supporting structure for said chamber providing a vertically disposed solidified gas charge-receiving chamber positioned spaced from said solidified chamber, said supporting structure forming a guideway from said solidification chamber to and across said receiving chamber, a movable transfer unit mounted in said guideway and providing a vertical charge transfer chamber therethrough, and 20 the said transfer unit movable in the guideway between charge-receiving position below and in vertical prolongation of the solidification chamber and a position above and vertically aligned with said charge-receiving chamber for discharge 25 thereto.
- 30 18. An apparatus for gas solidification and pressing, including in operative combination, separate gas solidification chambers, a press unit including a solidified gas pressing chamber having a pressing plunger therein, and transfer units movable between positions at and in gas-tight charge-receiving communication with said solidification chambers, respectively, and a position 35 in gas-tight charge-discharging communication with said press unit for transferring charges of solidified gas from the solidification chambers to the pressing chamber of the press unit.

19. In apparatus for gas solidification and 40 pressing, a gas solidification chamber, a solidified gas charge-holding chamber spaced from the solidification chamber, a press unit including a pressing chamber for receiving a charge of solidified gas from said charge-holding chamber and a transfer unit movable between a position in 45 gas-tight communication with and for receiving a charge of solidified gas from the solidification chamber, and a position in gas-tight communication with said charge-holding chamber for 50 discharging such charge into said holding chamber.

20. In gas solidification and pressing apparatus, the combination of, a gas solidification chamber, a press unit having a pressing chamber spaced from said solidification chamber for receiving a charge of solidified gas and for pressing such a charge into a block, and a solidified gas charge transfer unit movable between a position in 55 gas-tight communication with the solidification chamber to receive a charge of solidified gas from said chamber, and a position in gas-tight communication with the pressing chamber of

the press unit for discharging the charge of solidified gas to said pressing chamber.

21. In apparatus for pressing a solidified gas, in combination, separate sources of solidified gas, a pressing unit for receiving and pressing charges of solidified gas from said sources into blocks, separate means for each solidified gas source for transferring charges of solidified gas therefrom to said pressing unit, and each of said charge-transferring means being constructed 5 and arranged to maintain a charge of solidified gas therein sealed from the atmosphere and being also adapted for gas-tight communication with its respective solidified gas source and for gas-tight communication with said pressing unit. 15

22. In apparatus for pressing a solidified gas, in combination, a source of solidified gas, a pressing unit for receiving and pressing charges of solidified gas from said source into blocks, and means for transferring charges of solidified gas 20 from said source to said pressing unit, the said means being constructed and arranged for gas-tight communication with said source and for gas-tight communication with said pressing unit and also being designed to maintain a charge of 25 solidified gas therein sealed from the atmosphere during transfer from said source to said unit.

23. A unitary apparatus for gas solidification and pressing, including in operative combination, separate sources of solidified gas, a pressing 30 unit including a pressing chamber for pressing charges of solidified gas from said sources into blocks, and means for transferring a charge of solidified gas from any one of said sources to the press unit for discharge of the charge from 35 said means into the pressing chamber of said unit.

24. A unitary apparatus for gas solidification and pressing including in combination, separate gas solidification chambers, a solidified gas 40 charge-receiving chamber spaced from said solidification chambers, means for transferring a charge of solidified gas from any one of said solidification chambers to said receiving chamber, and a solidified gas pressing unit having a 45 pressing chamber for operative association with said charge-receiving chamber to receive a charge of solidified gas from said receiving chamber.

25. In apparatus for gas solidification and 50 pressing, in combination, a source of solidified gas, a chamber spaced from said source for receiving and holding a charge of solidified gas, a solidified gas pressing chamber for receiving a charge of solidified gas from said charge holding 55 chamber, and a transfer unit movable between a position receiving a charge of solidified gas from said source and a position discharging such charge into the charge-holding chamber. 60

26. A unitary gas solidification and pressing apparatus, including, in combination, a gas solidification chamber, a pressing chamber spaced from said solidification chamber for receiving a charge of solidified gas for pressing therein into a block, and a solidified gas charge transfer unit movable between a position at the solidification chamber to receive a charge therefrom and a position at the pressing chamber to discharge its charge of solidified gas into the pressing 65 chamber. 70
